UNITED STATES PATENT OFFICE.

R. S. WILLIAMS, OF BAIRDSTOWN, GEORGIA.

IMPROVEMENT IN PLOWS.

Specification forming part of Letters Patent No. 28,930, dated June 26, 1860.

To all whom it may concern:

Be it known that I, R. S. WILLIAMS, of Bairdstown, in the county of Greene and State of Georgia, have invented a new and Improved Plow; and I do hereby declare that the following is a full, clear, and exact description of the same, reference being had to the annexed drawings, making a part of this specification, in which—

Figure 1 is a side view of my invention. Fig. 2 is a transverse vertical section of the same, taken in the line $x x$, Fig. 1. Fig. 3 is an inverted plan of the same.

Similar letters of reference indicate corresponding parts in the several figures.

This invention relates to an improvement in that class of plows which are generally known as "shovel-plows," and are used in the cultivation of crops which are grown in hills or drills.

The object of the invention is to obtain a simple, economical, and durable plow of light draft, and one that may be managed or manipulated with the greatest facility.

To enable those skilled in the art to fully understand and construct my invention, I will proceed to describe it.

A represents the beam of the plow, which beam may be constructed of inch and a quarter plank of taper form, said beam being ten or twelve inches in depth at its back part, and about three inches in depth at its front end. On the back part of the beam A there is secured a cross-piece, B, the ends of which are fitted in the handles C C, and serve as a brace to the same.

D is the foot, which is of cast-iron of curved form, and forked at its upper end. The upper end of the back prong, a, of the foot is fitted in the under side of the beam A, but the front

prong, b, is provided with a socket, E, into which the beam A fits, a bolt, c, passing through the beam and the upper part of the socket. The socket E, at each side of the beam A, has a pocket or chamber, d. These pockets or chambers, as well as the socket E, are cast with the foot D, and they are inclined so as to receive the ends of the handles C C. The lower end of the foot D is curved forward, as shown clearly in Fig. 1, and there is a longitudinal dovetail slot, e, in the foot, into which projections f, at the under side of a share, F, fit, the projections being of dovetail form and, in connection with the slot e, securing the share to the foot.

By this construction a very simple and efficient plow is obtained. The handles, by the arrangement described, are firmly retained in proper position, and the implement is rendered quite light as well as strong, as but few parts are used.

I do not claim the connecting of the share F to the foot D by means of the dovetail slot e and projections f; but

I do claim as new and desire to secure by Letters Patent—

1. The casting of the foot D with a socket, E, and pockets d, substantially as shown, to receive the beam A and the lower ends of the handles C C, substantially as described.

2. In connection with the sockets E and pockets d, the brace or cross-piece B and taper-beam A, the former being attached to the beam and handles, as described.

R. S. WILLIAMS.
